(No Model.)

H. H. SATER.

CULTIVATOR.

No. 276,718.

Patented May 1, 1883.

UNITED STATES PATENT OFFICE.

HANS H. SATER, OF DUBUQUE, IOWA.

CULTIVATOR.

SPECIFICATION forming part of Letters Patent No. 276,718, dated May 1, 1883.

Application filed January 8, 1883. (No model.)

To all whom it may concern:

Be it known that I, HANS H. SATER, of Dubuque, in the county of Dubuque and State of Iowa, have invented a new and useful Improvement 5 in Cultivators; and I do hereby declare that the following is a full, clear, and exact description of the same.

My invention relates to an improvement in cultivators; but it relates more particularly to 10 improved coupling devices for connecting the plow-beams to the axle and frame-work, the object being a simple and inexpensive construction, easy in adjustment and operation, and durable and effective in use.

15 The invention consists, first, in the peculiar novel construction and arrangement of the coupling proper; further, in peculiar stops or sleeves on the axle for limiting the movement of the axle-sleeve; further, in peculiar draft-at- 20 taching devices; and, finally, in the general construction of the cultivator, and in novel details and combinations, all fully hereinafter explained.

25 The invention is illustrated in drawings which accompany this specification, and in which Figure 1 is a perspective view of the axle, one of the beams, and the coupling. Fig. 2 is a side elevation of the coupling. Fig. 3 is a detail of the cross-block; Fig. 4, a detail of the corner-clip; Fig. 5, a detail of the sand-cap for the axle; Fig. 6, details of the coupling; Fig. 7, a modification of the fork-connection.

30 A in these drawings represents the arched axle of a cultivator, constructed of course of metal, and having at each end a plain bearing for the carrying-wheels.

35 B represent the plow-beams, and C one of the couplings by which the beams are connected to the axle.

40 The horizontal part of the axle, on each side of the central arch, is made cylindrical to receive a sleeve, D, having a correspondingly cylindrical internal bore and a flat front face, 1, horizontally serrated or corrugated. This sleeve is prevented from having any longitudinal movement on the axle, first, by corner-clips E, Fig. 4, at the base of the arch; and, second, by sand-caps F on the axle between 45 the sleeve and the carrying-wheel bearings.

45 The corner-clips are composed of a tubular portion, 2, which is clamped upon the base of

the arch by a bolt and ears 4 4 and projections 5 5 6, which are bent down, as shown in Fig. 1, and bind firmly upon the axle, the projection 6 forming a stop against which the axle-sleeve bears, and by which, as before remarked, any longitudinal movement of the latter is prevented.

55 The sand-caps F are shown in Fig. 5. They are of tubular form and are provided with ears 7 7, by which they are clamped upon the axle, and with a projecting shield or cap, 8, which extends over the bearing of the carrying-wheel and prevents the dust and grit from entering. 65 The draft-attaching devices are connected to these caps, and also braces which support the tongue. Similar braces for the tongue are also connected to the clips E.

60 G represents a toothed sleeve, adapted to engage with the serrated face of the axle-sleeve D. This sleeve is shown in detail in Fig. 6. It is provided near each end with a true cylindrical bearing, 8, and at the upper end with a squared projection, 9. A bolt, H, passes 70 through the sleeve, and is secured rigidly to it by a washer, 10, having a square countersink, 11, which fits over the projection 9 on the sleeve. At the lower end the bolt H is squared, as at 12, while the internal bore of the sleeve 75 80 is of similar shape.

75 I is the fork-connection. (Shown separately in Fig. 6.) Its lower arm, 13, has an eye, 14, which works freely upon the lower bearing of the sleeve G. The attachment of the fork I to the upper bearing of the sleeve G is made through an independent eye, J, having a perforated arm, 15, provided with a notch, 16, and shoulder 17. The fork I and eye J are connected by a bolt, K, and when the parts are 90 in position the end of the fork bears against the shoulder 17, while the notch 16 engages with the end of a rib, 18, formed integral with the fork. The fork when in place has a free horizontal movement on the bearings. 95

80 The toothed sleeves are held in close contact by the peculiar loop shown at L, which has two horizontal links or eyes, 19, with a space, 20, between them. The loop is slipped over the axle-sleeve, while the sleeve G is passed through 100 the links, (see Figs. 1 and 2,) and a set-screw, 21, draws the parts together. It will now be readily apparent that a universally-yielding coupling is provided, the vertical movement

being that of the horizontal sleeve on the axle, while the fork moves horizontally on the bearings upon the vertical sleeve.

M N are the drag-bars. They are connected by means of bolts to arms 22, formed solid with or attached to the rear end of the fork. The bars are connected by a cross-bar, O. (Shown separately in Fig. 3.) This block has flanged and beveled ends 23 to partly inclose the bars which are bolted to it by pins passing through slots 25, by which the outside bars can be raised or lowered. A hole, 24, is also provided, to which the handle-brace is attached.

In Fig. 7, I have shown a modified form of fork-connection adapted to wooden drag-bars, the construction of which will be readily understood from the drawings.

Having described my invention, I claim—

1. The combination, with the axle and its toothed sleeve, of the vertical toothed sleeve G, engaging with the said sleeve on the axle, and having bearings formed directly upon its ends, and a bolt passing through said sleeve and bearings, a drag-bar, and the fork I, connected to the drag-bars and mounted upon the bearings on the ends of the said sleeve G, substantially as described.

2. The combination of the axle and its toothed sleeve, the vertically-toothed sleeve G,

having bearings at its ends, the drag-bar, the 30 forked connection I, connected to the drag-bar and mounted on the bearings of the sleeve G, and the loop embracing the said axle and sleeve G, and having the set-screw, substantially as described.

3. Combined with the arched axle A, the clip E, having ears 44 for attaching the tongue-braces, and the prongs 55, adapted to be bent down to bear directly upon the axle at the base of the arch, for the purpose set forth.

4. The combination, with the vertical sleeve connected to the axle-sleeve, of the fork having one arm connected directly to the bearing or journal formed on such vertical sleeve, and the eye J, which forms the connection between the other arm of the fork and the sleeve G.

5. Combined with the drag-bars M N, the cross-block O, having brace-connection 24, beveled and flanged ends 23, and the adjusting-slots 25 in such ends, substantially as described.

In testimony whereof I have signed my name to this specification in the presence of two subscribing witnesses.

HANS H. SATER.
